UNITED STATES PATENT OFFICE.

CARL VOSS, OF NEW YORK, N. Y.

SWITCH FOR ELECTRIC RAILWAYS.

SPECIFICATION forming part of Letters Patent No. 793,479, dated June 27, 1905.

Application filed April 1, 1905. Serial No. 263,326.

To all whom it may concern:

Be it known that I, CARL VOSS, a citizen of the United States, residing in New York, borough of Manhattan, in the State of New York, have invented certain new and useful Improvements in Switches for Electric Railways, of which the following is a specification.

This invention relates to an improved switch for electric and other railways which is so arranged that by foot-levers actuated by the motorman on the car-platform the switch-tongue may be operated at the proper time, so that the car can pass either in straight direction or to a side track, as required, without requiring a special attendant at the switch or the stopping of the car for setting the switch-tongue into the proper position; and for this purpose the invention consists of a switch for electric railways, which comprises foot-operated levers arranged on the car-platform, pivoted and spring-actuated setting shoes or blocks arranged in suitable casings at the under side of the car-platform for engaging and setting the switch-tongue, and intermediate lever connections between the foot-operated levers and the spring-actuated shoes or blocks, two of said setting-blocks being arranged at each side of the car vertically above each track-rail and tapered laterally at their lower ends, so as to either engage or clear the switch-tongue according as the switch-tongue is to be adjusted for one track or the other.

The invention consists, further, of certain details of construction and combinations of parts, which will be fully described herein-after and finally pointed out in the claims.

In the accompanying drawings, Figure 1 represents a side elevation, partly in section, on line 1 1, Fig. 2, of my improved mechanism for operating switches. Fig. 2 is a plan view, partly in section, through the parts below the platform, showing the lever mechanism for operating the switch-tongue-setting blocks or shoes. Fig. 3 is a vertical transverse section on line 3 3, Fig. 2. Fig. 4 is a plan view of the main and branch tracks, showing the arrangement of the switch-tongues and location of the setting-blocks for shifting the same. Fig. 5 is a horizontal section, through the casing of the

setting-blocks, on line 5 5, Fig. 1; and Fig. 6 6 is a detail vertical transverse section on line 6 6, Fig. 4, drawn on a larger scale.

Similar letters of reference indicate corresponding parts.

Referring to the drawings, A represents the platform of an electric or other railway car. At the front end of the platform, adjacent to the dashboard of the same, are arranged three foot-levers B B' B'', the foot-lever B being shorter and arranged at the middle of the platform and curved so as to give a good rest for the foot, while the side levers B' B'' are made longer and extended toward the sides of the platforms. The middle foot-lever B is pivoted to the upper ends of two vertical pusher-rods b b, while the side levers B' B'' are each pivoted at their outer ends to pusher-rods b' b'', which are guided in sleeves d^x, that are inserted into holes of the platform and attached to the same. In the lower parts of the sleeves d^x are guided auxiliary pusher-rods c c' c'', which are pivotally connected at their lower ends with the lower arms of elbow-levers e³, which are fulcrumed to a transverse pivot-shaft e⁴, supported in hanger-brackets e⁵, that are attached to the under side of the car-platform, as shown clearly in Fig. 1. One of the side foot-levers, as B', is pivotally connected with one of the pusher-rods b of the middle foot-lever B, while the other side foot-lever B'' is connected with the second pusher-rod of the middle foot-lever B, so that on depressing either one of the levers two pusher-rods are depressed, one outer and one inner, according to the connection of the foot-levers and pusher-rods, as shown in Figs. 2 and 3. The upper arms of two adjacent elbow-levers e³ are connected by pivot-rods f with two pairs of spring-actuated levers D, which are pivoted at their upper ends to a casing D', that is bolted to the under side of the platform A, said casing being step-shaped, as shown clearly in cross-section in Fig. 5, and arranged at an angle of inclination to the horizontal platform, so that the levers D are supported in inclined position, as shown in Fig. 1. One casing D' and two levers D are arranged at each side of the platform vertically above the track-

rails. The lower ends of the levers D are formed in the shape of blocks or shoes d d , which are arranged, like the levers, one behind the other and at the same distance from each other as the offset formed in the supporting-casings D'. The face of one pair of blocks or shoes is inclined in one direction, while the face of the adjacent pair of shoes is inclined in the opposite direction, as shown in Fig. 2. When either one of the foot-levers is depressed, the corresponding pair of setting shoes or blocks d , connected with the foot-lever, one setting shoe or block at each side of the track, is moved against the tension of the springs, acting on its lever in forward and downward direction, so as to move close to the track-rails and enter at the proper time into the enlarged recesses t of the switch-rails around the front ends of the switch-tongues T, as shown in Fig. 4, so as to engage that switch-tongue which is required to be shifted according to the direction of motion of the car and shift the same to one side or the other. If the right-hand switch-tongue is to be shifted, the right-hand foot-lever B² is depressed, so that the right-hand setting shoe or block d engages the switch-tongue and shifts the same over toward the right, whereby the car is compelled to move on the right-hand branch track, while when the car is to go over on the left-hand track the left-hand foot-lever B' is depressed and the left-hand switch-tongue moved over, while the right-hand switch-tongue is set by the shoe on the opposite side into proper position, so that the car is moved over on the left-hand branch track. When the car is to be moved straight ahead, the central foot-lever B is operated, and thereby the lower ends of the inner setting-shoes at both sides of the track depressed, so that both switch-tongues are moved sidewise for clearing the middle track and permitting the car to go straight ahead. In this manner by simply depressing the left-hand, right-hand, or central foot-lever the switch-tongues of the main and branch tracks are placed in proper position for permitting the movement of the car in the direction desired, either to one or the other side or straight ahead. The depressions t of the switch are provided at both sides and ends with inclines t' t'' , which permit the gradual descending and ascending motion of the setting-blocks in entering or leaving the depressions. These inclined portions produce the reliable action of the blocks on the switch-tongues without jars or concussions. As soon as the pressure on the foot-levers is released the shifting-blocks are returned by the pressure of the springs d' on their levers into normally raised position, as shown in Fig. 1, so that the blocks are supported at some distance above the track without interfering with the motion of the car over the same.

65 The switch-operating mechanisms can be

readily attached to the under side of the platform of any car, while the guide-sleeves for the pusher-rods are set into holes bored into the car-platform, so that the foot-levers can be readily applied to the upper ends of the same independently of the mechanism supported below the platform.

The motorman can be readily instructed how to properly operate the switch-operating blocks or shoes by depressing the central right or left hand lever with his foot, so as to cause the lowering of the proper switch-setting blocks according as the car is to go on straight ahead or on to the left or right hand branch track. When the car arrives at the end of the line, the foot-levers and pusher-rods pivoted thereto are removed from one end of the car and transferred to and placed into position at the opposite end of the car, so as to be used for actuating the setting-blocks below the opposite platform in the same manner as herein described.

Having thus described my invention, I claim as new and desire to secure by Letters Patent—

1. In a railway-switch, the combination, with central and side foot-levers arranged on the car-platform, of pusher-rods connected with said levers, switch-setting levers arranged in pairs one at each side of said platform, and intermediate lever mechanism connecting said pusher-rods with said switch-setting levers.

2. In a switch for electric railways, the combination, with central and side foot-levers arranged on the platform, of pusher-rods connected with said foot-levers, switch-setting levers arranged in pairs one at each side of the platform above the track, casings provided with offsets for said shifting-levers, setting blocks or shoes at the lower ends of said levers, the shoes of each pair of levers being provided with faces having inclinations in opposite direction to each other, and intermediate lever mechanisms connecting the pusher-rods with the lower ends of the switch-setting levers so as to produce the actuation of a shifting-block or shoe at each side by the central left-hand or right-hand foot-levers ascending, as the switch-tongue is to be shifted for the main or either branch tracks is to be placed in proper position.

3. In a switch for electric railways the combination with a central left-hand and right-hand foot-lever arranged on the platform, and pusher-rods pivoted to said foot-levers, of sleeves in said platform for guiding the pusher-rods, auxiliary pusher-rods below the pusher-rods on the foot-levers, inclined and step-shaped casings attached to the under side of the platform one on each side of the same, spring-actuated levers provided in said casings and pivoted with setting blocks or shoes at their lower ends, each pair of shoes at the same side of the platform having faces inclined in opposite direction, and intermediate lever mechanisms between the auxiliary

pusher-rods and the lower ends of the switch-setting levers for lowering the setting-blocks and shifting the switch-tongues for moving the car into the main or side track according as the central or other side foot-lever is depressed.

In testimony that I claim the foregoing as

my invention I have signed my name in presence of two subscribing witnesses.

CARL VOSS.
